UNITED STATES PATENT OFFICE

MAX A. MONTGOMERY, OF HUDSON, OHIO

TRUSSSED STRUCTURE

Application filed February 17, 1930. Serial No. 428,939.

My invention relates to trussed structures, which may be used as walls, but which are particularly adapted for use as floors and/or roofs in residential, office, commercial, and industrial buildings and the like.

More particularly my invention relates to cellular trussed structures preferably made of formed sheet or strip metal, preferably steel.

Most floor structures include joist members spanning between and being supported at their ends on bearing members which may be bearing walls or may be beams or girders which in turn are supported at their ends upon other beams or girders or upon columns or bearing walls.

The joint members are laterally spaced from each other, and support upon their upper chords or flanges some form of flooring or roofing, and may carry below their lower chords or flanges some form of ceiling.

Many different types of metal joists have been proposed for use in floor structures, and the flooring used for such joists is usually some form of concrete slab usually laid upon metal lath supported by the joists, or may be wood flooring secured directly to the joists.

In any event, steel joists are relatively difficult to fabricate for variable spans and variable loadings, and the placement of steel joists with the accompanying flooring in a building is relatively difficult and usually requires specially skilled labor for any particular type of joist floor structure.

Moreover, the complete floor including the joists and the flooring and the ceiling, requires the assemblage of materials usually from two different sources, since the manufacturers of joists rarely supply the necessary materials for the floorings and the ceiling.

The objects of the present improvements include in general the provision of a cellu-

lar trussed structure including interfitting chord and web members, for use primarily in buildings, and which may extend between and be supported by frame members of the building, and which may form preferably a load sustaining partition between the frame members, such partition, when extending vertically being usually designated as a wall, and when extending horizontally being usually designated as a floor.

More particularly the objects of the present improvements include the provision of a cellular trussed structure particularly adapted for use as a floor structure, and which includes a plurality of interlocking and interfitting members, all of which are preferably made of sheet or strip material, preferably of steel, and which result in a completed floor structure having flooring above, ceiling below, and interfitting and interlocking joist members between the flooring and ceiling members, whereby the improved floor structure may be placed in a building by the use of relatively unskilled labor, and such floor structures being adapted for variable spans and for variable loadings without necessitating excessive engineering and design cost.

Further objects of the present improvements include the provision of a trussed cellular structure adapted for use as a floor structure and including interfitting members, the several members being adapted for easy and economical manufacture, and being adapted for easy and economical erection in the building.

Further objects of the invention include the provision of a floor structure enabling the elimination of the use of concrete in many types of buildings.

These and other objects are attained by the present invention, the novel features of which are particularly set forth in the appended claims.

Preferred embodiments of my invention

are illustrated in the accompanying drawings forming part thereof, in which

Figure 1 is a fragmentary top plan view of a floor structure embodying the present improvements;

Fig. 2, a longitudinal sectional view thereof as on line 2—2, Fig. 1;

Fig. 3, an enlarged lateral sectional view thereof as on line 3—3, Fig. 1;

10 Fig. 4, an oblique view of another floor structure including a modified embodiment of my invention; and

15 Fig. 5, an oblique view of still another floor structure including a further modified embodiment of the present improvements.

Similar numerals refer to similar parts throughout the several views.

While the present improvements may be used in the walls of buildings, the load resisting truss action of the improvements is best attained in floors, and accordingly one floor structure embodying the present improvements is indicated generally at 10 in Figs. 1, 2, and 3, and preferably includes a plurality of panels each indicated generally at 11, and each panel includes a plurality of side by side longitudinally and laterally extending chord wall members 12, longitudinally and transversely extending web wall members 13, and longitudinally extending angled panel side members 14a and 14b.

Some of the chord wall members 12 are located in an upper plane and determine a floor wall, and some of the chord wall members 12 are located in a lower plane and determine a ceiling wall, and the web wall members 13 extend angularly between the spaced chord wall members 12 and form with the spaced chord wall members 12, a plurality of side by side longitudinally extending triangular cells 15.

The chord wall members 12 are preferably made of formed sheet or strip material, whereby the floor wall is continuous across each panel, and likewise the ceiling wall is continuous across each panel, and in certain classes of buildings such as industrial buildings, require no further covering. When desired however, a relatively shallow lay of material, such as asphalt, linoleum, fibreboard, or the like, may be used to surface the floor wall, and/or ceiling wall.

The web wall members 13 may be made of formed sheet or strip metal, as illustrated, or may be built up trussed joist structures when desired.

Each chord wall member 12 includes preferably at each side a longitudinally extending flange 16; and the flanges 16 are angular to the web 17 of the chord wall member 12, and extending from one face thereof and towards each other, and each flange forming with the web a hook.

65 The flanges 16 of the upper chord wall members 12 extend downwardly, and the

flanges 16 of the lower chord wall members 12 extend upwardly.

The apexes 18 between the flanges 16 and the webs 17 abut each other as illustrated, and the longitudinally extending abutting apexes 18 of the upper chord wall members 12 are preferably located midway between the abutting apexes 18 of the lower chord wall members 12 for obtaining the triangular formation of the cells 15.

70 Each web wall member 13 extends from hook engagement at one side between the flange 16 and the web 17 of a lower chord wall member 12 to a hook engagement at the opposite side with a flange 16 and a web 17 of an upper chord wall member 12; and each web wall member 13 preferably includes a web 19 and a longitudinally extending flange 20a at one side thereof, and a longitudinally extending flange 20b at the other side thereof, the flanges 20a and 20b being angular to the web 19, and extending away from opposite faces thereof, and form with the web an elongated Z as illustrated. The heads of the Z's are formed by the flanges 20a and 20b and the web, and the heads are interlockingly engaged by the hook flanges 16 of the members 12.

75 It has been found that this fundamental arrangement of the interfitting and interlocking members is not only practically self-sustaining, but is also adapted for carrying a relatively large superimposed load when the triangular cellular members are properly supported at their ends.

80 For increasing the rigidity and carrying capacity of the panel, the side members 14a and 14b are provided; and the side member 14a includes a lower ceiling web 21a having a longitudinally extending hook flange 22a at one side, and having a beam web 23a at the other side thereof, and the outer side of the beam web is provided with a longitudinally extending abutment flange 24a.

85 Similarly the side member 14b includes a lower ceiling web 21b having a longitudinally extending flange 22b at one side, and having a beam web 23b at the other side thereof, and the outer side of the beam web is provided with a longitudinally extending abutment flange 24b.

90 The side members 14a and 14b are provided for making a longitudinally extending rectangular panel.

95 Laterally extending end members 25 are provided for each panel 11, and each end member 25 has a laterally extending recess 26 formed therein into which the ends of the longitudinally extending members are fitted.

100 Each panel also preferably includes a plurality of laterally spaced tension members 27 arranged for applying a compression load on the longitudinally extending members, and as illustrated each tension member 27 is prefer-

ably in the form of a tie rod threaded at each end and extending through apertures in the end members 25, and each threaded end of each tie rod being provided with a nut 28, each nut abutting against the outer face of an end member, and being screwed against the end member for applying the desired compression load upon the longitudinally extending members.

10 Each panel 11 also preferably includes a laterally extending tension member 30 for applying a laterally directed compression and clamping load on the sides of the longitudinally extending members, and as illustrated the tension member 30 is in the form of a tie rod threaded at each end and extending through apertures in the members 13 and the beam webs 23a and 23b of the side members 14a and 14b, and each threaded end of 20 the tie rod is provided with a nut 31, each nut abutting and being screwed against the outer face of one of the panel side members.

15 A plurality of the panels may be utilized for making a floor of any desired area as illustrated in Figs. 1, 2, and 3, by the use of upper longitudinally extending filler members 32 and lower longitudinally extending filler members 33 positioned between the sides of adjacent panels, and by the use of laterally extending filler members 34 positioned between the ends of adjacent panels.

20 It will be seen that the interlocking and interfitting members are self-sustaining and easily fitted together, so that the cellular structure may be assembled on the ground or in position in a building structure.

25 Fig. 4 illustrates another floor structure including a modified embodiment of the improvements, indicated generally at 110.

30 The structure 110 includes a plurality of panels each indicated at 111 and each including a plurality of side by side longitudinally extending triangular tubular members 112, each preferably formed from sheet or strip metal and including a wall web 113 from the sides of which beam webs 114a and 114b extend away from one face of the wall web and towards each other and the outer sides of the beam webs are preferably provided, respectively, with longitudinally extending flanges 115a and 115b parallel with the wall web.

35 A plurality of wall members 116, each include at each side thereof a longitudinally extending snap flange 117 and the snap flanges of the wall members 116 make snap engagement between the apexes 118a and 118b, respectively; the apexes 118a and 118b being formed by the outer sides of the beam webs 114a and 114b and the flanges 115a and 115b.

40 Fig. 5 illustrates another floor structure 210 including a further modified embodiment of the present improvements, and the structure 210 is similar to the structure 10,

means being provided for bolting the longitudinally extending members to each other and for applying screed strips.

45 The structures 110 and 210 will be set forth in greater detail and the novel features thereof claimed in other applications for patent.

I claim:

1. A cellular trussed structure including two sets of side by side longitudinally and laterally extending chord members, one set 75 of the chord members determining one surface, and the other set of the chord members determining another surface transversely spaced from the first surface, web members extending longitudinally and transversely 80 between the sets of chord members and forming with the chord members a plurality of side by side longitudinally extending triangular cells, some of the chord members and some of the web members each including a longitudinally extending angled flange at one side thereof, the angled flanges of the chord members interfitting and interlocking with the angled flanges of the web members, and means joining the other sides of the 90 chord and web members with each other.

2. A cellular trussed structure including two sets of side by side longitudinally and laterally extending chord members, one set 95 of the chord members determining one surface, and the other set of the chord members determining another surface transversely spaced from the first surface, web members extending longitudinally and transversely between the sets of chord members and forming with the chord members a plurality of side by side longitudinally extending triangular cells, the chord members and the web members each including a longitudinally extending angled flange at each side thereof, 100 and the angled flanges of the chord members interfitting and interlocking with the angled flanges of the web members.

3. A cellular trussed structure including two sets of side by side longitudinally and laterally extending chord members, one set 110 of the chord members determining one surface, and the other set of the chord members determining another surface transversely spaced from the first surface, web members 115 extending longitudinally and transversely between the sets of chord members and forming with the chord members a plurality of side by side longitudinally extending triangular cells, some of the chord members and some of the web members each including a longitudinally extending angled flange at one side thereof, the angled flanges of the chord members interfitting and interlocking with the angled flanges of the web members, and means 120 joining the other sides of the chord and web members with each other, and end members for the structure, each of the end members having a recess formed therein, and the ends 130

of the chord and web members extending into the recesses.

4. A cellular trussed structure including two sets of side by side longitudinally and laterally extending chord members, one set of the chord members determining one surface, and the other set of the chord members determining another surface transversely spaced from the first surface, web members 10 extending longitudinally and transversely between the sets of chord members and forming with the chord members a plurality of side by side longitudinally extending triangular cells, the chord members and the web members each including a longitudinally extending angled flange at each side thereof, and the angled flanges of the chord members interfitting and interlocking with the angled flanges of the web members, and end members 15 for the structure, each of the end members having a recess formed therein, and the ends of the chord and web members extending into the recesses.

5. A cellular trussed structure including 20 two sets of side by side longitudinally and laterally extending chord members, one set of the chord members determining one surface, and the other set of the chord members determining another surface transversely spaced from the first surface, web members 25 extending longitudinally and transversely between the sets of chord members and forming with the chord members a plurality of side by side longitudinally extending triangular cells, some of the chord members and some of the web members each including a longitudinally extending angled flange at one side thereof, the angled flanges of the chord members interfitting and interlocking with 30 the angled flanges of the web members, and means joining the other sides of the chord and web members with each other, and end members for the structure, each of the end members having a recess formed therein, and 35 the ends of the chord and web members extending into the recesses, and tension members connecting the end members and applying a compression load on the chord and web members.

6. A cellular trussed structure including 40 two sets of side by side longitudinally and laterally extending chord members, one set of the chord members determining one surface, and the other set of the chord members determining another surface transversely spaced from the first surface, web members 45 extending longitudinally and transversely between the sets of chord members and forming with the chord members a plurality of side by side longitudinally extending triangular cells, the chord members and the web members each including a longitudinally extending angled flange at each side thereof, and the angled flanges of the chord members 50 interfitting and interlocking with the angled

flanges of the web members, and end members for the structure, each of the end members having a recess formed therein, and the ends of the chord and web members extending into the recesses, and tension members connecting the end members and applying a compression load on the chord and web members.

7. A cellular trussed structure including 55 two sets of side by side longitudinally and laterally extending chord members, one set of the chord members determining one surface, and the other set of the chord members determining another surface transversely spaced from the first surface, web members 60 extending longitudinally and transversely between the sets of chord members and forming with the chord members a plurality of side by side longitudinally extending triangular cells, some of the chord members and some of the web members each including a longitudinally extending angled flange at one side thereof, the angled flanges of the chord members interfitting and interlocking with the angled flanges of the web members, 65 and means joining the other sides of the chord and web members with each other, and end members for the structure, each of the end members having a recess formed therein, and the ends of the chord and web members 70 extending into the recesses, and tension members connecting the end members and applying a compression load on the chord and web members, and another tension member applying a laterally directed load on the chord and web members.

8. A cellular trussed structure including 75 two sets of side by side longitudinally and laterally extending chord members, one set of the chord members determining one surface, and the other set of the chord members determining another surface transversely spaced from the first surface, web members 80 extending longitudinally and transversely between the sets of chord members and forming with the chord members a plurality of side by side longitudinally extending triangular cells, the chord members and the web members each including a longitudinally extending angled flange at one side thereof, and the angled flanges of the chord members 85 interfitting and interlocking with the angled flanges of the web members, and end members for the structure, each of the end members having a recess formed therein, and the ends of the chord and web members 90 extending into the recesses, and tension members connecting the end members and applying a compression load on the chord and web members, and another tension member applying a laterally directed load on the chord and web members.

9. A cellular trussed structure including 95 two sets of side by side longitudinally and laterally extending chord members, one set 100

of the chord members determining one surface, and the other set of the chord members determining another surface transversely spaced from the first surface, web members
5 extending longitudinally and transversely between the sets of chord members and forming with the chord members a plurality of side by side longitudinally extending triangular cells, some of the chord members
10 and some of the web members each including a longitudinally extending acute angled flange at one side thereof, the angled flanges of the chord members interfitting and interlocking with the angled flanges of the web
15 members, and means joining the other sides of the chord and web members with each other.

In testimony that I claim the above, I have
hereunto subscribed my name.

20 MAX A. MONTGOMERY.
